UNITED STATES PATENT OFFICE.

WILLIAM S. DUNN AND WILLIAM F. MILLER, OF MIAMI, FLORIDA.

DIVING-HOOD.

1,195,793.

Specification of Letters Patent. Patented Aug. 22, 1916.

Application filed February 4, 1915. Serial No. 6,152.

To all whom it may concern:

Be it known that we, WILLIAM S. DUNN and WILLIAM F. MILLER, citizens of the United States, residing at Miami, in the 5 county of Dade and State of Florida, have invented new and useful Improvements in Diving-Hoods, of which the following is a specification.

This invention relates to improvements in 10 divers' apparatus, proposing more particularly an improved diving hood which is specially constructed whereby it may be worn without the usual diving suit and is complete in itself as the diving armor 15 equipment.

The objects of the invention are to provide a diving hood for use as stated, which may be instantly applied and removed, which, although applied without special 20 fastenings, remains securely in position upon the body, which by virtue of special features of construction facilitates the descent of the diver and enables the diver to work with the greatest ease and in any position 25 that he may be required to assume, and which may be simply and economically constructed and embodies no parts that are peculiarly liable to breakage or derangement.

30 An embodiment of the invention is illustrated in the accompanying drawings, wherein:—

Figure 1 is a perspective view of a diving hood in which the features of the invention 35 are incorporated; Fig. 2 is a front elevation thereof; Fig. 3 is a vertical sectional view thereof; and Fig. 4 is a top plan view thereof.

Similar characters of reference designate 40 corresponding parts throughout the several views.

The improved diving hood which is made of metal or rigid material has a generally bell or dome shape and in the embodiment 45 shown is of substantially uniform diameter throughout its extent. The hood is valveless and is closed except at its lower end which is so formed and proportioned that the hood may be instantly fitted in position 50 over the head or removed therefrom without the manipulation of any parts whatever. The hood has the lower edges of its side portions formed along curves as at 2 which conform generally to the shoulder 55 curvature of the human body, and when in use is simply fitted over the head and rests,

without positive attachment, upon the shoulders of the diver, as shown in Fig. 3. For the purpose of holding the hood in position upon the diver's shoulders and of facilitating the diver's descent, the hood has its lower portion weighted at opposite sides thereof, preferably at the front and rear. In a preferred embodiment of the invention, the weights, indicated at 3 are detachable from the hood and are held in position by hooks or other devices 4 carried by the hood and engaging through openings in the weights 3. The lower edges of the hood at the front and rear thereof come below the diver's shoulders and the weights 3 which are arranged adjacent the lower edges of the hood at the front and rear thereof are accordingly disposed in symmetrical relation to the approximate center of buoyancy 75 of the body.

The hood has in its lower portion, preferably closely adjacent its lower edge and at one side thereof, a suitable number of openings 5 for the escape of air, and these openings, in the preferred embodiment of the invention, are altogether valveless. The provision of the openings 5 for the escape of air is preferred but other expedients for the same purpose may be adopted independently of or in combination with said openings. Thus, the curvature of the edges 2 may be so selected as to provide for air escape spaces between the diver's shoulders and the lower edges of the hood.

The hood is equipped with the usual sight glass 6 and in its upper portion with an air inlet connection 7 to which the usual air hose 8 may be joined. The hood is also provided at its upper end with a suitable handle by which it may be carried from place to place or lifted from the shoulders of the diver, upon his ascent to the surface of the water.

In use, the hood is placed over the head 100 until it rests on the shoulders, as shown in Fig. 3, and the weights 3 maintain the hood in position upon the body of the diver and facilitate the diver's descent through the water. The arms and legs of the diver are 105 thus perfectly free and the diver may work more quickly and with greater facility than would be the case were his arms and legs hampered by the usual diving armor. By virtue of the arrangement of the weights 3, 110 as described, the diver may assume any position in the water which the particular work

in hand may require without any liability of the hood becoming displaced. The air pressure within the hood displaces the water therefrom and is prevented from undue accumulation by the openings 5 through which the air escapes in opposition to the water pressure. The pressure of air within the hood need be no greater than is required to hold the water in the hood at some determined level, for instance, the level of the highest points of the curved edges 2 and, hence, regardless of the depth at which the diver may work, is much lighter than the pressure required with the ordinary rubber diving armor. For this reason, the use of the hood is not liable to cause injury to the ears owing to excessive pressure against the ear drums, as is the case with the ordinary rubber diving armor. Since the air pressure required is relatively light, an ordinary hand pump, which may be included in the equipment of every small boat, may be used as the means for generating the air pressure.

25 The hood may be instantly removed without the manipulation of any part thereof by simply lifting it from position. This ready removability of the hood serves a number of advantages. When ready to ascend, the diver may remove the hood, allowing it to fall upon the bottom of the body of water in which he is working and quickly float to the surface. Or, it may happen that the air hose will be too short, say by eight or ten feet, to enable the diver to reach a particular object sought, such a condition being extremely likely of occurrence in exploring wrecks, in which case, the diver may remove the hood, placing it in some readily accessible position and carrying an anchor or weight in one hand may walk the necessary distance to secure the object sought and then return to the hood and place it in position, such operation in no way interfering with his remaining below the surface of the water. Again, in the event that the pump or the air hose becomes deranged, the diver is not imprisoned, as in the ordinary armor, but may remove the hood and rise to the surface by virtue of the natural buoyancy of his body.

30 The weights 3 are preferably made separable from the hood, not only to simplify and reduce the expense of construction, but also to enable the weights to be selected as the conditions of use may require and to be adapted to the individual physique of the diver.

35 The hood above described is complete in itself as a diving apparatus and entirely

eliminates any necessity for applying weights to the feet or to other parts of the body. It has been found capable of efficient use by persons who have had no experience in diving, since it is entirely devoid of any manipulatable parts or valves whose proper adjustment requires a measure of previous experience with the use of diving armor.

Having fully described our invention, we claim:

1. A diving hood comprising a valveless 70 body of rigid material closed except at its lower end and having its lower end formed and shaped whereby the hood may be fitted in operative position over the diver's head and shoulders and instantly and freely removed from said position, the lower edge of the hood being curved at its sides to conform to the curvature of the shoulders of the body and the hood having adjacent its lower edge and at the front and rear thereof weight means to insure the stability of the hood upon the diver's shoulders without the positive attachment of the hood to the body and to facilitate the diver's descent through the water, the hood having a sight glass and 80 an air inlet connection for attachment to a supply hose, and the lower portion of the hood being formed to permit the escape of air into the water.

2. A diving hood comprising a valveless 90 body of rigid material closed except at its lower end and having its lower end formed and shaped whereby the hood may be fitted in operative position over the diver's head and shoulders and instantly and freely removed from said position, the lower edge of the hood being curved at its sides to conform to the curvature of the shoulders of the body and the hood having adjacent its lower edge and at the front and rear thereof weight 95 means to insure the stability of the hood upon the diver's shoulders without the positive attachment of the hood to the body and to facilitate the diver's descent through the water, the hood having a sight glass and an 100 air inlet connection for attachment to a supply hose, and the lower portion of the hood being provided with valveless air escape passages open to the water in which the hood is submerged.

110 In testimony whereof we have hereunto set our hands in presence of two subscribing witnesses.

WILLIAM S. DUNN.
WILLIAM F. MILLER.
